(57) **CLAIM**

The ornamental design for a round dining table as shown and described.

DESCRIPTION

FIG. 1 is a top perspective view of a round dining table showing my new design;

FIG. 2 is a bottom perspective view thereof;

FIG. 3 is a front, back, left and right view thereof;

FIG. 4 is a top plan view thereof; and,

FIG. 5 is a bottom plan view thereof.

In the drawings, the broken lines show portions of the table that form no part of the claimed design.
